UNITED STATES PATENT OFFICE

129,323

DESIGN FOR A HANDLE FOR MIRRORS OR SIMILAR ARTICLES

Joseph A. Despres, Scarsdale, N. Y., assignor to Bernard Rice's Sons, Inc., New York, N. Y., a corporation of New York

Application April 1, 1941, Serial No. 100,081

Term of patent 7 years

To all whom it may concern:

Be it known that I, Joseph A. Despres, a citizen of the United States of America, residing at Scarsdale, in the county of Westchester and State of New York, have invented a new, original, and ornamental Design for a Handle for Mirrors or Similar Articles, of which the following is a specification, reference being had to the accompanying drawing, forming part thereof.

Figure 1 is a front elevational view of a handle for mirrors or similar articles showing my new design;

Figure 2 is a rear elevational view of the same;
Figure 3 is a side elevational view of the same; Figure 4 is a cross-sectional view taken on the line 4—4 of Fig. 1; and

Figure 5 is a similar view taken on the line 5—5 of Fig. 1.

I claim:

The ornamental design for a handle for mirrors or similar articles, substantially as shown.

JOSEPH A. DESPRES.
